(57) **CLAIM**

The ornamental design for a wall and ceiling fixture, as shown and described.

DESCRIPTION

FIG. 1 is a top and rear perspective view of the wall and ceiling fixture,

FIG. 2 is a top and left-side perspective view thereof,

FIG. 3 is a top and front perspective view thereof,

FIG. 4 is a bottom and left-side perspective view thereof,

FIG. 5 is another top and left-side perspective view thereof,

FIG. 6 is a bottom and right-side perspective view thereof,

FIG. 7 is a top planar view thereof,

FIG. 8 is a front elevational view thereof,

FIG. 9 is a left-side elevational view thereof,

FIG. 10 is a bottom planar view thereof,

FIG. 11 is a bottom and rear perspective view thereof,

FIG. 12 is a right-side perspective view thereof,

FIG. 13 is a front perspective view thereof,

FIG. 14 is a rear and right-side perspective view thereof,

FIG. 15 is a left-side perspective view thereof,

FIG. 16 is a rear and left-side perspective view thereof,

FIG. 17 is a front and right-side perspective view thereof; and,

FIG. 18 is a front perspective view thereof.
